UNITED STATES PATENT OFFICE

2,184,797

ICE TRAY

Harvey D. Geyer, Dayton, Ohio, assignor to General Motors Corporation, Detroit, Mich., a corporation of Delaware

Application May 7, 1937, Serial No. 141,234

8 Claims. (Cl. 62—108.5)

This invention relates to freezing trays such as are adapted for use in mechanical refrigerators for household use.

An object of this invention is to provide a very simple and efficient partitioning grid for such freezing trays from which the frozen ice blocks may be easily removed without any melting thereof by distorting the grid.

Another object is to provide an easily distortable grid which has some metal partition walls and some flexible non-metallic partition walls whereby to obtain faster freezing than is obtainable with a grid having all partition walls of flexible rubber or other non-metallic material.

Another object is to provide a freezing grid having a series of separate metal partition walls loosely joined together to form a relatively long non-rigid metal partition wall which may be easily distorted to facilitate the removal of the frozen ice blocks.

Further objects and advantages of the present invention will be apparent from the following description, reference being had to the accompanying drawings wherein a preferred embodiment of the present invention is clearly shown.

In the drawings:

Fig. 1 is a plan view of an ice tray and removable grid therein made according to this invention.

Fig. 2 is a section on line 2—2 of Fig. 1.

Fig. 3 is a section on line 3—3 of Fig. 1.

Fig. 4 is a detail view of one of the cross partitions.

Fig. 5 is a section on line 5—5 of Fig. 4.

Figs. 6 and 7 are side view and cross section respectively of one end element of the metal partition.

Figs. 8 and 9 are side view and cross section respectively of one intermediate element of the metal partition.

Figs. 10 and 11 are side view and cross section respectively of the other end element of the metal partition.

Similar reference characters refer to similar parts throughout the several views.

Numerical 10 designates the metal container pan which may be of any suitable design, but is preferably such that it may be distorted to loosen the ice and grid as a unit therefrom, such as that disclosed in applicant's copending application Serial No. 88,559, filed July 2, 1936.

The removable grid comprises a series of separate metal sections 11, 12, and 13 loosely attached together to form the central longitudinal partition wall designated as a whole by numeral 15.

The end metal section 11 is preferably flat with a vertical slot 17 at one edge thereof as shown in Figs. 6 and 7. The other end metal section 13 has an offset edge portion 16 having a vertical slot 17 therein (see Figs. 10 and 11). The intermediate metal sections 12 each has a similar offset edge portion 18 with a vertical slot 17 therein and also a vertical slot 17 at the other vertical edge thereof. All the intermediate sections 12 may be made identical in form as shown in Figs. 8 and 9, and every alternate section 12 may be simply reversed top for bottom to obtain the arrangement shown in Fig. 1. When the metal sections 11, 12, and 13 are all arranged in slightly overlapping relation as shown in Fig. 1, the vertical slots 17 will register at each overlap.

The flexible non-metallic cross partitions 20 are shaped as shown in Figs. 4 and 5 and are preferably cut to shape from a flat sheet of flexible rubber or other suitable flexible non-metallic material which may be easily peeled from the frozen ice blocks bonded thereto. These flexible cross partitions 20 are slotted out at slots 22 to provide a central neck portion 21 of such dimensions as will fit snugly within the registered slots 17 in the overlapping metal sections and thereby yieldably hold said metal sections together.

The parts are assembled together in a very simple and efficient manner as follows. The wide portions of the cross members 20 are sufficiently flexible and stretchable as to be threaded thru the aligned slots 17 in two overlapping metal sections simply by inserting a corner of member 20 thru the slot 17 and then pulling half of the flexible member 20 thru said slot until the neck portion 21 snaps into place and substantially fills the slot 17. The edges of slots 22 form yielding shoulders which abut snugly against the lateral surfaces of the overlapping metal sections and so retain these overlapping portions in mutual lateral contact.

In operation, the removable grid is set down into the pan 10 either before or after pan 10 is filled with water to the desired level. The pan is then set within a freezing compartment until the ice is solidly frozen. To remove the ice blocks from the tray, the grid and ice contents are first removed from the pan as a unit by any suitable or presently known method. The grid may then be readily flexed by hand by bending or twisting same from end to end or by any other suitable distortion thereof to cause the ice blocks to loosen therefrom. Since the central metal partition wall is composed of metal sections yieldably joined together so as to be relatively movable

in any direction by a distortion of the flexible and stretchable neck portions 21, it is obvious that the grid as a whole is readily subject to the above-mentioned manual distortion.

5. While the embodiment of the present invention as herein disclosed, constitutes a preferred form, it is to be understood that other forms might be adopted, all coming within the scope of the claims which follow.

10. What is claimed is as follows:

1. A freezing tray having a removable grid, said grid comprising a plurality of metal partitioning members and a plurality of flexible rubber partitioning members, said metal members being

15 yieldably held together by said rubber members.

2. A freezing tray having a removable grid, said grid comprising a series of separate metal partition walls arranged in substantial alignment to form a composite partition wall, and a series 20 of flexible rubber partition walls, said metal partition walls being yieldably held together by said rubber partition walls.

3. A freezing tray having a removable grid, said grid comprising a series of separate metal 25 partition walls having slightly overlapping portions, and a series of flexible rubber partition walls intersecting said overlapping portions and yieldably holding said overlapping portions together.

30. 4. A freezing tray having a removable grid, said grid comprising a series of separate metal partition walls loosely joined together to form a relatively long non-rigid partition wall, and a series of flexible rubber partition walls, said separate metal walls being loosely joined together by 35 said rubber walls.

5. A freezing tray having a removable grid, said grid comprising a main longitudinally expansible metal partition wall having longitudinally expansible joints therein and a series of separate flexible rubber partition walls extending transversely across said metal wall and secured thereto. 5

6. A freezing tray having a removable grid, said grid comprising a series of separate metal partition walls having slightly overlapping slotted 10 portions having substantially aligned slots therein, and a series of flexible rubber partition walls intersecting said overlapping portions and having flexible rubber portions extending through said aligned slots in said metal walls. 15

7. A freezing tray having a removable grid, said grid comprising: a main longitudinal metal partition wall having expansible joints therein which facilitate bending of said main wall in its longitudinal plane, and a series of flexible rubber cross 20 partition walls extending transverse to said main wall and carried thereby.

8. A freezing tray having a removable grid, said grid comprising: a main longitudinal metal partition wall having expansible joints therein 25 which facilitate bending of said main wall in its longitudinal plane, and a series of readily distortable rubber cross partition walls extending across said main wall and forming therewith two rows of ice block compartments, said cross walls 30 being distortable by the bending of said main wall in its longitudinal plane, to facilitate the removal of the frozen ice blocks therefrom.

HARVEY D. GEYER. 35
